Primary Examiner — Catherine S Posthauer*Assistant Examiner* — Yen Le Southwood*(74) Attorney, Agent, or Firm* — George D. Morgan(57) **CLAIM**

The ornamental design for a vegetable cutter, as shown and described.

DESCRIPTION

FIG. 1 is a top perspective view of a vegetable cutter, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the vegetable cutter, which form no part of the claimed design. The dash-dot-dash broken lines encircling the enlarged views are for annotative purposes only and form no part of the claim thereof.
